UNITED STATES PATENT OFFICE.

WILLIAM O. WHITNEY, OF GLENS FALLS, NEW YORK.

FOLDING UMBRELLA.

SPECIFICATION forming part of Letters Patent No. 699,731, dated May 13, 1902.

Application filed September 12, 1899. Serial No. 730,261. (No model.)

To all whom it may concern:

Be it known that I, WILLIAM O. WHITNEY, a citizen of the United States, residing at Glens Falls, in the county of Warren and State 5 of New York, have invented a new and useful Umbrella, of which the following is a specification.

This invention relates to folding umbrellas, and has for its object to provide an umbrella 10 of this class which can be folded into small and compact form for transportation and storage in a grip or other receptacle of small compass and one which at the same time will be as strong and durable in use as umbrellas of 15 ordinary types, which are not capable of such manipulation.

"Folding umbrellas," as that term is understood in the art, comprise ribs of sectional form designed to be folded and carried by a 20 sectional stick or rod capable of being disjointed, so that the entire structure may be carried within a receptacle of a length little greater than that of one of the rib-sections.

One of the primary objects of the invention, 25 therefore, is to simplify and strengthen the joints between the rib-sections and to connect the spreaders with the ribs in a manner to permit the entire manipulation of the umbrella, whether in use or when folding it into 30 small compass, by means of a runner movable upon the stick and designed to effect the expansion and contraction of the radially-disposed series of spreaders.

Viewed in a somewhat more limited aspect 35 the object of the invention is to provide the hingedly-connected rib-sections of each rib with an interlocking connection with the adjacent section and with the adjacent spreader, the relation of the spreader to the rib-sections, 40 being such that the raising and lowering of the rib in use may be effected through the medium of the spreader without disturbing the interlocking connection between the rib-sections, or the interlocking connection may be 45 broken and the rib-sections folded one upon the other also through the medium of the spreader and runner.

A further object of the invention is to construct the umbrella-rib of two sections, one 50 of which is foldable upon the other and has slight longitudinal movement with respect thereto for the purpose of effecting the connection or disconnection of the locking mechanism carried by the sections and to effect

such longitudinal movement of one of the 55 rib-sections solely by the manipulation of the spreader, the latter being arranged when moved within normal limits to hold the rib-sections in interlocking engagement and when moved beyond such normal limits to 60 break the interlocking connection between the rib-sections to automatically effect the folding of said sections one upon the other.

A still further object of the invention is to improve the construction of the sectional handle, the runner, and the runner-latch, which objects, as well as others subordinate to those recited, will appear more fully hereinafter as the necessity for their accomplishment is developed in the course of the succeeding description of the preferred form of the invention illustrated in the accompanying drawings and embraced within the scope of the appended claims.

In said drawings, Figure 1 is an elevation 75 of the sectional umbrella-rod equipped with a rib and spreader constructed in accordance with my invention, the position of these parts when the umbrella is collapsed being indicated in dotted lines. Fig. 2 is an elevation 80 showing the rod-sections disorganized and the rib and spreader in their folded positions. Fig. 3 is a detail view, partly in section, of the upper end of the umbrella-rod, showing the connection of the ribs with the upper 85 notch rim or flange and the location of the rib receiving and spacing device therebelow. Fig. 4 is a section on the line 4 4 of Fig. 3.

Fig. 5 is a detail section of the portion of the rod containing the runner-latch, the latch 90 being shown in elevation. Fig. 6 is a transverse section on the line 6 6 of Fig. 5. Fig. 7 is a detail perspective view of the runner-latch. Fig. 8 is a detail section of the joint between the two rod-sections. Fig. 9 is an 95 elevation of one of the rod-joints. Fig. 10 is a detail view, partly in elevation, showing the locking connection between the rib-sections and the spreader, the parts being shown in their engaged positions. Fig. 11 is a view 100 similar to Fig. 10, showing relative positions of the parts after the spreader has been actuated to move the outer rib-section longitudinally for the purpose of disengaging the locking device preparatory to the folding of the 105 rib. Fig. 12 is a view similar to Fig. 11, showing the subsequent position of the parts during the folding operation, the spreader

having been further moved from the position indicated in Fig. 11 to cause the disengaged inner end of the outer rib-section to be swung downwardly and outwardly and the outer 5 end of the outer rib-section to be swung back above the inner rib-section. Fig. 13 is a similar view showing the position of the parts subsequent to the position shown in Fig. 12, the spreader being shown as moved to what is 10 called its "folded" position, at which time it will have effected the complete folding of the outer section upon the inner section of the rib. Fig. 14 is a perspective view showing the parts interlocked or engaged as in Fig. 15, 15 but in the positions they assume when the umbrella is being lowered. Fig. 15 is a detail sectional view on the line 15 15 of Fig. 10. Fig. 16 is a view similar to Fig. 8, but showing a somewhat-different arrangement 20 of the rod-latch. Fig. 17 is a section on the line 17 17 of Fig. 16, and Fig. 18 is a detail view showing a portion of the umbrella-cover and illustrating the inwardly-curved outer edges of the cover-gores.

25 Referring to the numerals employed to designate corresponding parts throughout the views, 20 and 21 indicate the upper and lower tubular sections of the umbrella-rod, tapering somewhat toward its upper end, prefer- 30 ably made of metal and fitted with a tapering tip 22. The lower end of the hollow upper section 20 of the rod constitutes a socket for the reception of a short joint-plug or rod-section 23, the opposite end of which is snugly 35 fitted in the rod-section 21 and held by any suitable means—as, for instance, a rivet 24. The projecting portion of the joint-plug 23, which latter, if desired, may be formed integral with the lower rod-section, is provided 40 with a longitudinally-disposed slot 25, extending inwardly approximately to the center of the rod, a perforation 26 piercing the plug 23 at the base of the slot and opening into the latter adjacent to the upper end of 45 the plug. The slot 25 is designed for the reception of a rod-latch constructed of spring metal and having a transversely-rectangular base 27, from which is extended a longitudi- 50 nal spring portion 28, formed at or adjacent to its end with a laterally-extending head or finger-piece 29, designed for engagement with a slot 32 in the lower end of the tubular rod-section 20. This slot 32 is preferably enlarged at its center by a circular perforation 31, which 55 permits the finger-piece 29 to be readily depressed, notwithstanding that said finger-piece or head is normally flush with the surface of the rod to prevent its interfering with the movement of the runner, to be described.

60 Various means for retaining the rod-latch in place may be devised; but this end is preferably accomplished by means of a laterally-disposed lug 30, formed integral with the base portion 27 and seated in the perforation 26 in 65 the joint-plug or short rod-section 23. By reference to Fig. 8 of the drawings it will be readily understood that the joining of the rod-

sections is effected by slipping the section 20 over the projecting end of the plug 23 to effect a rigid connection of the sections by the 70 engagement of the rod-latch with the section 20. Adjacent to the base of the rod-tip 22 is located, as usual, the integral or otherwise-formed notch-rim 35 for the reception of the inner ends of the umbrella-ribs, and for the 75 attachment of the inner ends of the spreaders 38 a runner 36 is slidably disposed upon the rod and carries a similar notch-rim 37, in a manner well understood in the art. The runner 36 is flared at both ends, as shown, to facilitate 80 its engagement with the runner-latch either above or below the latter, the projecting lug or catch-piece 39 of said latch having its outer face curved, as shown, to facilitate its depression by the runner as the latter is 85 presented to it from either direction. The lug or catch-piece 39 of the runner-latch projects outwardly through a slot 40 in the rod-section 20, the ends of the lug being flat for direct engagement with the end walls of a 90 longitudinal slot 41, formed in the runner in a manner well understood in the art and designed for the reception of the lug 39.

The runner-latch, which, as stated, carries at its free end the finger-piece or lug 39, comprises a narrow spring-stem 42, provided with a laterally-extending lug 43, adjacent to the end opposite the lug 39 and designed to engage a perforation 44 in the rod-section 20. From this lower end of the latch, or, more 100 properly, from the stem 42 thereof, extends upwardly and divergently a spring-arm 45, which engages the inner surface of the tubular section 30 at the side opposite the perforation 44 and serves to exert a spring-pres- 105 sure tending to hold the lug 43 in its aperture and augmenting the resiliency of the spring-stem 42 for the purpose of normally retaining the head or lug 39 in its projected position, as best shown in Fig. 6 of the drawings. It 110 is evident that the spring 45 serves a dual function in that it effects the retention of the runner-latch within the rod by insuring the engagement of the lug 43 with said rod and exerts more or less spring-pressure, which is 115 auxiliary to the inherent resiliency of the spring-stem 42, so that while the spring 45 yields somewhat when the lug 39 is depressed such yielding does not interfere with the proper retention of the latch against longitu- 120 dinal movement within the stem.

We have now seen in what manner the sections of the umbrella-rod are jointed and how the runner is constructed and retained in position upon the rod, and we now come to a consideration of that feature of the invention which is of primary importance in the production of a practical umbrella of the folding type. The feature to which reference is made is the peculiar construction and arrangement 125 of the ribs and spreaders, whereby said spreaders are utilized to effect the locking and un-locking of the rib-sections, the raising and lowering of the ribs when the umbrella is in

use, and the folding of the ribs when it is desired to store or transport the umbrella in a case of small compass. In short, we are now to consider the peculiar and novel construction and arrangement of parts whereby the operator by manipulating the runner upon the rod may effect the raising, lowering, and folding of the ribs or the unfolding of the latter through the medium of the spreaders attached to the ribs and runner in the peculiar manner which makes the foregoing manipulation a possibility.

The ribs of the umbrella each comprise two sections—an inner section 46, pivotally connected to the notch-rim 35 at one end, and an outer section 47, arranged for connection at its outer end with the umbrella-cover. The general form of these ribs is not essential; but the adjacent ends of the rib-sections are preferably flattened, as indicated in Figs. 10 to 13 of the drawings. The ribs are thus formed to facilitate the attachment of a pair of locking elements or members 48 and 51. The member 48 projects inwardly—that is to say, toward the rod—from the end of the rib-section 47 and is provided in its upper face with a groove, slot, or depression 49, the side walls of which terminate in a pair of parallel ears 50, between which is pivoted by a combined pivot and locking-bar 50 the outer end of a spreader 38, it being observed that the spreader, which is of course connected to the runner at its inner end, is pivotally connected at its outer end to the inner extremity of the outer rib-section 47 through the medium of the locking-bar 50. The other locking element or member 51 is secured to the outer end of the inner rib-section 46 and is designed for reception for a suitable portion of its length within the slot or depression 49 of the locking member 48 and with its outer end disposed closely adjacent to the rear end of said slot. The outer end of the locking member 51 is preferably somewhat enlarged, as shown, and is provided with a longitudinally-disposed slot 52, through which is passed a pivot-pin 53, forming a pivotal connection between the two locking elements, but permitting slight relative longitudinal movement of the two rib-sections by reason of the lateral play of the pivot-pin 53 within the slot 52. Inasmuch as the locking members may be considered portions of the ribs, it will now be seen that the outer rib-section has a loose pivotal connection at a point intermediate of its ends with the outer end of the inner rib-section and has a fixed pivotal connection at its inner extremity with the outer end of a spreader, the term "fixed pivotal connection" being employed for the reason that this connection is not shiftable relative to either of the connected elements—that is to say, it is not shiftable with respect to either the spreader or the outer rib-section, as distinguished from the pivotal connection between the two rib-sections, which is designed to shift somewhat in order to permit

the outer rib-section to have slight longitudinal movement independent of the inner rib-section. Before going further, therefore, it may be observed that the outer rib-section may be swung upon the outer end of the inner rib-section as a fulcrum by the manipulation of the inner end of the outer section 47, and it will also appear that as the inner end of the outer section 47 is connected to the spreader the angular disposition of the spreader with respect to the outer rib-section will determine the relation of the rib-sections to each other—that is to say, (see Fig. 11,) if the pivotal connection between the section 47 and the spreader 38 is disposed in a plane above a line extending through the axis of the pivot-pin 53 and touching the inner end of the spreader the angle of the spreader will be such as to force the inner end of the outer rib-section 47 against the under side of the inner rib-section 46, thereby presenting said rib-sections in substantial alinement and permitting them to be raised in unison by the elevation of the runner in the usual manner. On the other hand, however, if the runner is elevated to such an extent as will bring the axis of the pivot-pin 50 below a line drawn in the manner indicated, or even to bring the three points stated in substantial alinement, the inner end of the outer rib-section 47 will drop away from the inner section 46, and as the joint or knuckle formed between the spreader and rib-section 47 is thus broken the parts will swing inwardly (see Fig. 12) until the spreader and the two rib-sections are folded in close relation, as indicated more clearly in Fig. 13, it being evident that the inward swinging of the inner rib-section and of the spreader from different centers will cause the outer rib-section to be swung upon the pivot-pin 53 as an axis until it is folded back upon the inner section 46. In other words, the relative positions of the parts are governed by the knuckle-joint formed at the connection between the spreader and the outer rib-section, and the angular relation of the spreader with respect to the rib will therefore determine whether or not the rib-sections will be maintained in alinement to permit the raising and lowering of the ribs in the ordinary use of the umbrella or whether, on the contrary, the outer rib-section will be folded upon the inner rib-section to permit the total collapse of the device for transportation or storage.

By reference to Fig. 1 of the drawings it will be seen that when the runner 36 is in engagement with the runner-latch the angle of the spreader will be such as to maintain the alined position of the two rib-sections, so that the several ribs will be supported in the position usually assumed by the ribs of umbrellas when raised. It will also appear that if the runner is dropped below the latch the relation of the spreader to the rib will not be changed in a manner to cause the relative swinging of the rib-sections. On the contrary, if the runner is dropped below the latch

the effect will be to permit the rib as an entirety to swing inwardly and downwardly toward the umbrella-rod—as, for instance, in the manner of an ordinary umbrella when 5 closed. If, however, the runner is disengaged from the runner-latch and is moved an appreciable distance above it, the spreader 38 and the outer rib-section 47 will be disposed in such approximate alinement as will permit 10 the knuckle-joint between these members to be broken downwardly, (see Fig. 12,) the slight longitudinal movement of the outer rib-section facilitating this changing of relation of the parts. As before stated, this downward 15 breaking of the joint or pivotal connection between the spreader and rib-section 47 will permit the latter to have independent pivotal movement, and as this will permit the inner rib-section and the spreader to swing downwardly toward the rib the result will be to 20 effect the complete folding of the umbrella by the simple act of elevating the runner to a position sufficiently above the runner-latch. This relation of the parts—that is to say, of 25 the rib-sections and spreader—would be productive of a completely-operative device without further additions, so far as this particular feature of the invention is concerned. Such would not, however, be the highest development 30 of the invention, because the knuckle-joint between the spreader and rib-section would be most too sensitive, and an unskillful user or operator might therefore have some difficulty in properly manipulating the 35 ribs in accordance with his desires. I therefore prefer to provide the rib-sections with locking mechanism and with means for yieldingly resisting the longitudinal movement of the outer rib-section necessary to the breaking 40 of the joint, the locking mechanism being so organized as to be automatically disengaged or released by the longitudinal movement of the outer rib-section, such movement, by reason of the resistance imposed, being 45 possible only by a positive intentional manipulation of the runner and its attached spreader. This rib-section locking mechanism comprehends a locking-hook 56, depending from the under side of the locking member 51, preferably at or adjacent to the inner end of the latter and opening outwardly—that is to say, the hook 56 opens toward the outer end of the inner rib-section 46 and is 50 designed to engage the pintle or locking-pin 50', constituting the pivotal connection between the spreader and outer rib-section and whose axis is the axis of the knuckle-joint, to which attention has been called. Thus when 55 the locking-hook 56 is in engagement with the locking-pin 50 the joint is held against downward breaking, and the folding of the outer rib-sections is thereby prevented until the locking-pin has been moved laterally toward the outer end of the inner rib-section a sufficient 60 distance to effect its disengagement from the hook 56. At such time the joint may be broken downwardly and the outer rib-section

folded, provided the spreader 38 bears such angular relation to the rib as will make possible this manipulation of the parts. The 70 resistance opposed to the longitudinal movement of the outer rib-section is designed, however, for the purpose of preventing such disengagement of the locking-pin 50 from the hook 56 except upon the exertion of a 75 positive pressure, such as would only ordinarily be exerted with intention to effect the disconnection. This resistance mechanism comprehends a spring finger or hook 54, connected at its inner end to the under side of 80 the locking member 51 and disposed substantially parallel with the member, as clearly shown in Figs. 11 to 13 of the drawings. The outer portion of the hook or finger 54 is provided with a laterally-deflected end 85 designed to yieldingly engage a recess 55, formed in the bottom wall of the slot 49 in the locking member 48. By reference to Fig. 10 it will be seen that the deflected extremity of the spring 54 is designed to be seated within 90 the recess when the locking-pin 50 is in complete engagement with the hook 56 and when the pin 53 is at the inner end of the slot 52 in the locking member 51 of the inner rib-section. It will therefore be evident that in order to 95 cause the disengagement of the locking-pin 50 from the locking-hook 56 the outer rib-section must be urged longitudinally with sufficient force to overcome the resistance opposed to such movement by the spring-finger 54. 100 Another function of the spring-finger 54, which will be obvious from careful consideration of the unlocking operation, is that the spring will exert more or less tendency to swing the outer rib-section upon its axis, because the spring-finger must be more or less compressed to cause its withdrawal from the recess, and this compression will be exerted to 105 swing the inwardly-extended end of the outer rib-section away from the inner rib-section 110 as soon as the locking-pin 50 has passed out of engagement with the locking-hook 46 and is no longer sustained thereby. With the parts constructed and related in the manner specified the runner may be reciprocated upon 115 the umbrella-rod sufficiently to effect the raising and lowering of the umbrella in the usual manner without interfering with the connection between the rib members, because such slight outward pressure as may be exerted upon the outer rib-section by the spreader will be successfully resisted by the finger 54 and by the cover of the umbrella, which is connected to the outer ends of the ribs and opposes more or less resistance to 120 that outward movement of the outer rib-section which is necessary to effect the unlocking of the two rib-sections. Supposing, however, that the parts are in the positions indicated in Figs. 1 and 10 and that it is desired 125 to fold the umbrella for transportation or storage in a small case. (See Fig. 2.) In this event the runner-latch will be depressed to permit the runner 36 to be moved upwardly 130

beyond the latch a sufficient distance (see Fig. 11) to cause great outward pressure to be exerted upon the outer rib-section 47. The force thus applied will overcome the resistance of the spring finger or check 54 and the holding power of the cover and will move the outer rib-section 47 longitudinally a sufficient distance to shift the pin 53 to the outer end of the slot 52 and to cause the locking-pin 50' 10 to move out of engagement with the locking-hook 56. The downward breaking of the joint will now be assisted more or less by the spring-finger 54, and the inward swinging of the inner rib-section and spreader will cause the outer rib-section to fold upon the inner rib-section in a manner which will be apparent from a perusal of Figs. 12 and 13. The umbrella proper having thus been folded solely by the manipulation of the runner the 15 rod-section 21 may be detached from the section 20 by the manipulation of the rod-latch in an obvious manner. On the other hand, when it is desired to reorganize the umbrella for use the rod-section is attached, and instead of manipulating the folded rib-sections by hand in the usual manner the runner is simply moved down the rod to the position indicated in dotted lines in Fig. 1, when, as will be evident, the outer rib-sections will swing 20 back by gravity to the position shown in dotted lines in Fig. 1, and from this position the umbrella is raised to the full-line position of Fig. 1 by the elevation of the runner in the usual manner. It will therefore appear that 25 the manipulation of the runner not only controls the raising, lowering, and folding of the umbrella, but also effects the unfolding thereof for use and the automatic engagement and disengagement of the mechanism which either 30 connects the rib-sections or permits the folding thereof, as desired.

By reference to Figs. 14 and 15 of the drawings it will be seen that the outer ends of the spreader 38 are bifurcated, so that its ends or 35 bifurcations lie outside of the planes of the ears 50, between which the locking-hook 56 is received for engagement with the locking-pin. In umbrellas of this character where a number of movably-connected parts are employed it is highly desirable to provide for 40 their retention in properly-spaced relation when the ribs are folded, so as to prevent jamming, crowding, or rattling of the parts. This end is attained in large measure by the 45 provision of a guide or receiver 60, preferably in the form of a rubber ring, having a series of peripheral notches in spaced relation and designed for the reception of the individual ribs when the latter are folded alongside of 50 the rod, as illustrated in dotted lines in Fig. 3. The resiliency of the rubber guide serves not only to prevent the abrasion of the ribs or rod, but also tends to positively hold the ribs against outward movement, as the 55 notches in the receiver or guide are made somewhat smaller in transverse section than the ribs, so that when the latter are forced

into the notches the resiliency of the rubber will tend to positively hold the ribs against movement, while spacing them in their proper 70 relative positions. It will also now be clear that the flaring of the runner at its opposite ends is not a mere matter of duplication, but is made necessary by the fact that the runner is designed to engage the runner-latch from 75 positions both above and below the latch, and the special utility of the particular form of runner-latch will also appear, because the latch is designed to hold the runner equally against movement in either direction, so that 80 the ribs will not only be retained in their raised positions, but will also be retained unfolded by the retention of the spreader at the proper angle. In Figs. 16 and 17 of the drawings is shown a modification of the rod-latch, 85 the lower rod-section 61 being provided with a splicing-rod 62 therein, projecting therefrom for engagement with the lower end of the rod-section 63, provided with an opening 64. In this form of rod-joint the splicing or 90 connecting rod 62 is formed with a longitudinal slot 65, extending throughout its length, for the reception of a rod-latch 66, constructed in a manner similar to the construction of the rod-latch illustrated in Fig. 8, except that it 95 is provided additionally with a recess 67 in one edge, through which the rivet 60, holding the splicing or connecting rod in place, is passed.

From the foregoing it will be observed that 100 I have produced a simple, ingenious, and effective folding umbrella wherein the ribs are manipulated in use or are folded entirely by the manipulation of the runner; but while the present embodiment of the invention appears 105 at this time to be preferable I do not limit myself to the structural details employed, but reserve the right to make such changes, modifications, or variations of the illustrated structure as may be properly comprehended 110 within the scope of the protection prayed.

What I claim is—

1. The combination with a tubular portion having a perforation therein and a slot, of a spring-plate comprising a base, a lug adjacent one end of the base and engaged with the perforation of the tubular portion, a spring-stem forming a continuation of the opposite end of the base and lying out of contact with the tubular portion at its rear end, a head 115 upon the forward extremity of the spring-stem and lying in the slot of the tubular portion and adapted for reciprocation therein, and a spring-finger extending from the spring-stem and disposed in the same direction therewith and divergently therefrom, the extremity of the spring-finger lying against the tubular portion at the opposite side from the perforation to hold the lug in the perforation and to reinforce the spring action of the stem. 120 125 130

2. In an umbrella-rod, the combination with a tubular section, of a rod therein and having a longitudinal slot in one face, a perforation in the base of the slot, a latch-tongue dis-

posed in the slot and having a lug at one edge engaging the perforation, the opposite edge of the latch-tongue lying against the inner face of the tubular portion to hold the lug in engagement, a perforation through the tubular portion and the rod, a recess in the spring-tongue alining with the perforations, and a rivet passed through said perforations and recess to hold the parts in position.

- 10 3. In a folding umbrella, the combination with rib-sections and a spreader, of interlocking and pivotally-connected lock elements carried by the rib-sections, connections between one of said elements and a spreader for 15 holding the elements in mutual engagement, a recess in one of the elements, and a spring-finger carried by the other element and adapted for engagement with the recess to hold the elements in their locking positions, said spring 20 being also adapted to move the elements upon their pivotal connection when they are unlocked.

4. In a folding umbrella, the combination with rib-sections and a spreader, of a lock element carried by each section and having pivotal engagement with each other, said elements being movable longitudinally with respect to each other to lock and unlock them, connections between the spreader and one of 30 said elements for moving it longitudinally with respect to the other element and a spring carried by one element and adapted for engagement with the other element to move the elements upon their pivotal connection when 35 they are unlocked.

5. The combination with a rib-section having a grooved lock element fixed thereto, of a second rib-section, having a lock element fixed thereto, said second lock element lying 40 in the groove of the first element and having a longitudinal slot, a pivot-pin passed through the walls of said groove and through the slot and adapted to play in the latter to permit mutual longitudinal movement of the elements, a pin carried by the first element, a hook adapted for engagement and disengagement with respect to the pin, connections between a spreader and one of said lock elements to move the latter with respect to the 45 second element to engage and disengage the hook with the pin and a spring-finger carried by one of the elements and adapted for engagement with the other element when the lock is engaged with the pin, said finger being 50 adapted to move the elements on their pivot when the hook is disengaged from the pin.

6. The combination with a rib-section having a locking element provided with a longitudinal groove, of a second rib-section having 60 a locking element seated in said groove and having pivotal and longitudinal connection with the first-named element, a pin carried by the first element, a hook carried by the second element and adapted for engagement 65 with the pin to hold the rib-sections together, a spreader pivotally connected with the first element and adapted to move it longitudi-

nally of the second element to engage and disengage the hook with the pin and a spring-finger carried by one of the elements and adapted for engagement with the other element when the lock is engaged with the pin, said finger being adapted to move the elements on their pivot when the hook is disengaged from the pin. 75

7. The combination with a rib-section having a locking element fixed thereto and comprising a hook and a spring-tongue, of a second rib-section having a locking element pivoted to the first-named element, the second element having a recess to receive the spring-tongue and having a pin adapted to engage the hook subsequent to the engagement of the spring-tongue with the recess, and a spreader connected with the second element and adapted 80 to move the pin into and out of engagement with the hook. 85

8. In a folding umbrella, the combination with inner and outer rib-sections and a spreader, of interlocking and pivotally-connected locking members carried by the rib-sections, and a fixed pivotal connection between the outer rib-section and spreader, whereby said spreader serves to hold the locking members in engagement, and means for 90 urging the rib-sections apart when the locking members are disengaged. 95

9. In a folding umbrella, the combination with an inner rib-section provided with a locking member formed with a longitudinal slot 100 and a locking-hook, of an outer rib-section having a second locking member provided with a pair of transverse pins designed respectively for engagement with the slot and hook of the other member, a spreader connected to the inner end of the second locking member to urge said members into and out of interlocking engagement, one of said locking members being provided with a recess, and the other of said members being provided 105 with a spring-finger disposed for engagement with the recess to resist relative longitudinal movement of the locking members. 110

10. In a folding umbrella, the combination with an inner rib-section, of an outer rib-section having a loose pivotal connection intermediate of its ends with the outer end of the inner rib-section, a spreader having pivotal connection with the inner end of the outer rib-section, means for locking the outer rib-section and the spreader to the inner rib-section, and a spring interposed between the two rib-sections at a point between the two pivotal connections above stated, said spring serving to effect the swinging of the outer rib-section when said section is unlocked. 115 120 125

In testimony that I claim the foregoing as my own I have hereto affixed my signature in the presence of two witnesses.

WILLIAM O. WHITNEY.
